WALL CORNER MOLDING

Ronald R. Sundelin, Roslyn Harbor, and Harry Feder, New York, N. Y., assignors to Barclay Manufacturing Co., Inc., Bronx, N. Y., a corporation of New York

Application March 16, 1953, Serial No. 342,386

4 Claims. (Cl. 20—74)

This invention relates to improvements in the construction of building walls, particularly interior walls, and more especially to an improved corner construction for such walls.

The general object of the invention is to provide an improved corner construction for walls made from prefabricated wall units or panels.

In the construction of walls from prefabricated units, difficulty has been experienced at the corners where two wall sections come together, and particularly projecting corners, that is to say, where the two sections come together to form a corner whose outside angle between the walls is 270°. The two wall units meeting at the corner usually can be made to approach into fairly close proximity to one another, but an open joint remains which is both unsightly and neither moistureproof nor soundproof. The present invention attacks this problem and provides a corner molding which is readily assembled between the proximate edges of the two corner wall units, and which provides a soundproof and moistureproof joint between the units. It also serves as a protection for the corner and gives it a neat and attractive appearance.

A further object of the invention is to provide such a molding which will afford both a soundproof and moistureproof joint between the units without the use of a caulk compound, or the like, and which at the same time, will provide for expansion and contraction of the wall corner units both vertically and horizontally, without affecting the tightness of the joint.

The invention will be understood by considering the accompanying drawings and the detailed description following. In these drawings:

Fig. 1 is a view in horizontal section taken on line 1—1 of Fig. 5 showing a projecting corner wall construction according to the present invention;

Fig. 2 is a perspective view illustrating one of the fixtures or spring clips used in mounting the wall units on the wall supports or studding;

Fig. 3 is a perspective view of the improved corner molding;

Fig. 4 is a plan view of a complete wall unit; and

Fig. 5 is a view in elevation looking from the right of Fig. 1, as indicated by the line 5—5, and drawn to a much smaller scale, both the upper and lower portions of the wall being shown broken away.

Referring now to these drawings and first to Fig. 4, the wall unit from which the two wall sections are constructed, as shown, is of a composite construction and comprises a body member 1 and a facing sheet 2 which are bonded permanently together by means of a layer of suitable adhesive 3. The body member 1 has a portion 4 which extends to the right beyond the edge of the facing sheet 2, and the facing sheet has a portion 5 which projects to the left overhanging the left edge of body member 1. If desired, however, the wall unit may be made in one piece. Along the right-hand edge of facing sheet 2 there is a recess 6 formed in the adjacent surface of the body extension 4, and seated and secured by adhesive in this recess there is a molding strip 7. This is made of flexible resilient material, and has oppositely projecting wing portions 8 and 9 for assisting in making a tight joint between the edges of the facing sheets 2 of contiguous wall units, as shown in Fig. 1.

2

The body member 1, in the composite construction shown, is preferably about three eighths of an inch (3/8") thick and the facing sheet member 2 about one eighth of an inch (1/8") thick making the overall thickness of the unit approximately one half of an inch (1/2"). These dimensions, however, can be varied to suit conditions. Advantageously the body member 1 is made of asphalt impregnated wood fiber insulating board, although it can be made of plasterboard, asbestos cement board, plywood, or the so-called sawdust boards, and other materials of this general character. The facing sheet member 2 is preferably made of tempered compressed wood fiberboard, but it can also be made of glass, or metal, or plastic, if desired.

15 The facing sheet member 2 is preferably provided with a suitable finish coating 10. Advantageously coating 10 is a synthetic baked enamel, such for example as an enamel made of alkyd and melamine resins, or modified alkyd melamine resins. Such coating, however, 20 may consist of an air-dried paint or of a sheet of suitable plastic material laminated to the surface of facing sheet member 2, or the coating 10 may consist of a suitable lacquer. It will be understood, however, that the surface of facing sheet 2 may be left unfinished, and the 25 wall painted in the usual manner, after installation.

Wall sections 11 and 12 (Fig. 1) are constructed by assembling wall units similar to the typical wall unit just described and shown in Fig. 4, and the details of the manner in which these units are assembled are set forth 30 in co-pending application No. 342,385, filed March 16, 1953. This assembling will be referred to here as briefly as possible.

The respective wall units A, B, C, and D forming the wall construction of Fig. 1 are mounted on the studding members 13, 14 and 15. Units A and C are attached to the studding by means of spring metal clips 16 (Fig. 2). These clips each have teeth 17 projecting at right angles from one end of the mid-section 16, and a shank 18 projecting at right angles from the opposite end of the mid-section. Shank 18 has a nail hole 19 near its outer end. The spring clips are placed in spaced relation along one edge of the wall panels. The teeth 17 are forced or worked into the panels as shown at the lower right and upper left of Fig. 1.

40 The right-hand portion of the wall shown in Fig. 1 will be constructed first, and it will be assumed that the wall has been finished up to and including panel A. This panel is held in position against the stud 13, and nails 20 are driven through the holes of shanks 18 of the spring clips. The panel section B is then placed in position by forcing its body member projection 4 beneath the facing sheet projection 5 of the panel A. This compresses, or takes the bow out of the spring shanks 18 of the metal clips 16 flattening the shanks as shown in Fig. 1, and this spring action keeps the parts tight. In forcing these panels A and B together, the respective shanks of the clips may cut, or form, recesses or depressions in the inner surface of the body member 1 of panel B. The two panels are worked together until the edge of the facing sheet 2 of panel B engages and somewhat compresses the resilient molding 7.

45 With panel B in position its opposite edge overlies the corner stud 14 with the facing sheet projection 5 of wall unit B preferably projecting beyond the surface 21 of stud 14. There is some leeway in the relative location of these two parts which is provided by the improved corner molding 22. This molding as shown in Fig. 3 comprises a thin base member 23 of considerable width and advantageously tapering to a relatively thin edge as shown more particularly in Fig. 1. Extending along the opposite or thicker edge of base member 23 and at right angles is a shank portion 24. This shank portion ter-

minates in two oppositely projecting wing portions 25 and 26 which are unsymmetrically arranged with respect to shank portion 24. These wing portions form, with shank portion 24 and base member 23, respectively, two recesses 28 and 30, recess 28 being substantially thinner than recess 30.

The molding is manufactured by a molding or extrusion process from a suitable flexible resilient material, which, advantageously, may be vinyl plastic. It also can be made of natural rubber, of synthetic rubber, such as neoprene, or combinations of these materials, or of any convenient material, which will provide the characteristics of flexibility and resiliency, particularly in the two wing portions 25 and 26. Before the molding is placed upon the wall, the wing portions 25 and 26 stand inwardly as indicated by the dotted lines in Fig. 3. The full line position of Fig. 3 corresponds with the positions of these portions as shown in Fig. 1.

The next operation is to mount the molding 22, and this is done by driving nails 27 through the holes 27a which are provided in spaced relation along the base member 23. In placing the molding, the wing portion 25 will be forced outwardly from the normal dotted position of Fig. 3 to the position of Fig. 1, when this wing is slipped over the facing sheet projection 5 of unit B. This projection is received in the recess 28 formed between the shank 24 and wing 25 which is now substantially parallel with the inner surface of shank 25. It will be understood that the pressure of wing 25 against projection 5 will not only form a tight soundproof and moistureproof joint from top to bottom of panel B, but it also mechanically supports this edge of panel B against the surface of stud 14.

Continuing the wall construction around the corner, panel C is first prepared for its application to studs 14 and 15 by applying the spring clips 16, as previously described, and further by sawing off along the opposite edge of the panel the portion shown in dotted lines in Fig. 4. The portion removed includes the entire body projection 4, the molding 7 and a portion of the edge of facing sheet 2 thereby leaving a flat edge 29 which is at right angles to the faces of the wall unit and forms square corners therewith.

Panel C thus prepared is placed with its square edge 29 within the recess 30 which is formed by the wing portion 26 of molding 22 and its base member 23. In doing this the wing portion 26 is forced outwardly from its normal dotted position, as shown in Fig. 3, to substantially parallel position with base 23, as shown in Fig. 1. The pressure of wing 26 along the surface of facing sheet 2 of unit C forms a tight joint at this point from floor to ceiling, and also wing 25 supports this edge of unit C against the surface of stud 14. The opposite or left-hand edge of unit C is now attached to stud 15 by means of nails 31 driven into the stud through the shanks of the respective spring clips.

In Fig. 1 the wall unit D is shown ready to have its body projection 4 forced over the outwardly positioned spring shank portions 18 of the spring clips and beneath the facing sheet projection 5 of unit C. The arrow is intended to indicate this movement.

By means of the improved corner construction including the molding 22, not only is a tight joint formed which is both soundproof and moistureproof, but also the adjacent edges of the two corner wall units B and C are firmly secured to the corner stud 14. In addition, however, and which is important, the construction of molding 22 affords a considerable degree of leeway in matching the sides of the wall units with the corner stud. For example, projection 5 of wall unit need not project clear to the bottom of its recess, a good seal is obtained if the projection is received only part way within this recess. Also, flexibility is possible in placing unit C, inasmuch as the edge 29 may be sawed at any desired point along the width of this unit. That is, for example, if required,

unit C, instead of being sixteen inches (16") wide to correspond with the usual stud spacing, might be only half this width, or even less.

It will be understood that changes in the arrangement of the corner construction can be made without departing from the spirit of the invention whose scope is intended to be set forth in the appended claims.

I claim:

1. A corner molding for a wall construction having wall supporting means, said molding comprising a single thin base member for attaching to the wall supporting means, a single shank portion extending along one edge of the base member at right angles thereto, a wing portion projecting from said shank portion and having an inner surface generally parallel with said shank, and a second wing portion projecting oppositely from said shank and having an inner surface generally parallel with said base member, said wings being supported entirely by said single shank portion.

2. A corner molding for a wall construction having wall supporting means, said molding comprising a single thin base member for attaching to the wall supporting means, a single shank portion extending along one edge of the base member at right angles thereto, a wing portion projecting from said shank portion and having an inner surface generally parallel with said shank, and a second wing portion projecting from said shank in the opposite direction and having an inner surface generally parallel with said base member, said wing portions being flexible and resilient and being supported entirely by said single shank portion.

3. A corner wall construction comprising wall supporting means, two wall units of the same thickness mounted on said supporting means at right angles to each other and having their edges in proximity to one another and forming a corner, one of said units having a projecting outer face portion overhanging the body portion thereof, a corner molding disposed between the proximate edges of said wall units, said molding having a base member attached to said wall supporting means, a shank portion extending along one edge of the base member at right angles thereto, and two wing portions projecting oppositely from said shank portion, one of said wing portions being generally parallel with said shank and forming therewith a recess, said projecting face portion of one of said units being received therein, and the second of said wing portions projecting generally parallel with said base member and forming therewith a second recess for receiving the entire thickness of the second of said wall units.

4. A corner molding for a wall construction having wall supporting means, said molding comprising a single base member for attachment to said wall supporting means, a single shank portion extending along one edge of the base member at right angles thereto, and two wing portions projecting oppositely from said shank portion, one of said wing portions forming therewith a recess, and the second of said wing portions forming with the base member a second recess, said wing portions each having a free edge and each being supported entirely by said single shank portion and being unsymmetrically arranged with respect to said shank whereby the central planes of said recesses are disposed at right angles to one another.
